CLAIM

The ornamental design for a retractable car charger, as shown and described.

DESCRIPTION

FIG. 1 is a front perspective view of a retractable car charger, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a perspective view of the design shown in an alternate position.

The broken lines in the drawings illustrate the portions of the retractable car charger, which form no part of the claimed design.
